UNITED STATES PATENT OFFICE.

JOHN E. W. FOGAL, OF QUINCY, ILLINOIS, ASSIGNOR TO FOGAL-WILLIAMS SAFETY DEVICES, INC., OF QUINCY, ILLINOIS, A CORPORATION OF ILLINOIS.

ELEVATOR INTERLOCKING DEVICE.

Application filed October 19, 1921. Serial No. 508,810.

To all whom it may concern:

Be it known that I, JOHN E. W. FOGAL, a citizen of the United States, and a resident of Quincy, in the county of Adams and State 5 of Illinois, have invented a new and useful Improvement in Elevator Interlocking Devices, of which the following is a full, clear, and exact description.

My invention relates to elevator interlocking devices, and it consists in the combinations, constructions and arrangements herein described and claimed.

An object of my invention is to provide a combination latch for elevator doors and interlocking safety device which is simple in construction and thoroughly effective for the purpose intended.

A further object of my invention is to provide a device of the character described in 20 which the electrical points of contact are thoroughly insulated.

A further object of my invention is to provide a device of the character described which may be readily attached to the ordinary type of elevator door.

A further object of my invention is to provide a device of the character described in which the safety device will operate when the latch is not engaged even though the 30 door of the elevator may be closed.

Other objects and advantages will appear in the following specification, and the novel features of the invention will be particularly pointed out in the appended claims.

My invention is illustrated in the accompanying drawings forming part of this application, in which

Figure 1 is a plan view of my interlocking device along the line 1—1 of Figure 2, 40 Figure 2 is a side elevation of my interlocking device,

Figure 3 is a view of my interlocking device operatively applied, and

Figure 4 is a perspective view of the 45 switch plunger.

In carrying out my invention, I make use of a cast metal base 1 having holes 2 therethrough for securing the base to the wall or like structure. On one side of the base 1 and adjacent the end thereof I provide an upwardly extending stationary cam member 3, the purpose of which will hereinafter be described. At the opposite end of the base 50 1 is an upwardly extending end wall 4 having an opening 5 therethrough to accommodate

a metal conduit 6 through which wires 7 and 8 may be lead.

A casing 9 of bakelite or other suitable material is secured to the base 1 by means of screws 10. The casing 9 has two side walls 11 and 12 and an end wall 13. The opposite end of the casing is closed by an end wall 14 which is placed at a short distance from the ends of the side walls 11 and 12, allowing the space 15 between the wall 14 and the end wall 4 of the base. The sides and ends of the casing 9 are all of the same height and are leveled so that a cover 16 may be so placed to close the casing 9. The cover is arranged to be held in place by screws 17 which are received in threaded openings 18 of the two end walls of the casing 9. A bottom 19 is provided and forms an integral part of the casing 9.

An upwardly extending metal contact post 20 is secured to the bottom 19 of the casing 9 and is provided with a set screw 21. A contact arm 22 of spring bronze or other suitable material is secured at one end to the end wall 14 of the casing 9 by means of a screw 23. A Z-shaped metal strap 24 is placed between the spring member 22 and the side of the end wall 14 and is also held in place by the screw 23. The member 24 has at its end a binding screw 25. An upwardly extending ridge 26 on the bottom 19 of the casing provides a rest as well as a guide for the movement of the spring member 22 toward and away from the contact member 20, as shown in dotted lines.

The side 11 of the casing has adjacent the cam member 3 a plunger 27 of bakelite or other suitable material which is flattened on one side to closely engage an end of the cam 3. This plunger extends within the casing and is normally held in the position shown in Figure 1 by means of the pressure exerted by the spring contact member 22. The shape of the plunger 27 is clearly shown in Figure 4. The surface 27' provides a means of limiting the outward movement of the plunger. A collar 29 on the inner surface of the wall 11 provides ample means for guiding the plunger 27 in its movement to and away from the surface 30 of the wall 11.

The wires 7 and 8 are arranged, one to be connected to the binding screw 25 and the other to the binding screw 21 and passage through the wall 14 is provided by an opening 31.

Referring now to Figure 3, the device above described is secured to the wall adjacent an elevator door 32. The door 32 is arranged to move upon a track 33 by means of rollers 34. An upwardly extending bracket 35 is provided at the top of the door 32 and supports, by means of the spring 36, a hook-shaped latch member 37. Movement of the latch 37 is brought about by means of a rod 38 which extends from the latch 37 to a bell crank lever 39 having a handle as shown at 40. The handle 40, when actuated, will draw the latch 37 down so as to disengage it from the cam member 3. This cam member 3 acts as a tooth and provides means of engagement for the latch member 37.

From the foregoing description of the various parts of the device, the operation thereof may be readily understood. The wires 7 and 8 are the ends provided by tapping of a continuous line contained in the conduit 41 which runs from one elevator door to another, and the current for supplying power to the elevator must flow through this line. It will therefore be evident that if the line is broken at any point, the elevator cannot be moved.

When the door 32 of the elevator is closed, the latch 37 will slide up the inclined surface of the cam member 3 and drop down behind the end 28 of that member, thus latching the door. The door cannot be opened until the latch 37 is pulled down by such means as provided by the hand lever 40. When the latch 37 falls down over the end 28 of the member 3, it pushes with it the plunger 27 which in turn presses the spring contact member 22 against the contact post 20 and establishes an electric circuit between the wires 7 and 8.

It will therefore be seen that if any of the doors are opened the elevator will not move, since the circuit supplying power for moving the elevator is broken.

I claim:

1. A device of the character described comprising a base, a cam surfaced tooth integral with said base, a casing of insulating material carried by said base, a pair of spaced apart contact members supported on said casing, said casing having an opening through one side thereof adjacent one end

of said cam tooth, and a plunger slidably mounted in said opening and adapted to bring one of said contact members into engagement with the other of said contact members when pressure is brought to bear thereon. 55

2. A device of the character described comprising a base, a cam surfaced tooth integral with said base, a casing of insulating material carried by said base, a contact post carried by said casing, a spring contact member carried by said casing and normally out of engagement with said contact post, said casing having an opening therethrough adjacent one end of said cam tooth, and a plunger slidably disposed in said opening and adapted to move said spring contact member to engage said contact post when pressure is brought to bear thereon. 60

3. A device of the character described, comprising a base, a cam surfaced tooth integral with said base, a casing of insulating material disposed on said base, said casing having an opening therethrough adjacent one end of said cam tooth, a contact post mounted within said casing, a spring contact member mounted within said casing and arranged to make contact with said contact post when pressure is brought to bear thereon, and a plunger slidably disposed in said opening in said casing and arranged to engage said spring contact member at one end and to project beyond the outer wall of said casing at the opposite end. 75

4. A device of the character described comprising a base, a cam surfaced tooth, a casing of insulating material disposed on said base, said casing having an opening therethrough adjacent one end of said cam tooth, a contact post carried by said casing, a spring contact member carried by said casing having its contact point normally spaced apart from said contact post, and a plunger slidably disposed in said opening, said plunger having engagement at one end thereof with said spring contact member and having its other end projecting out of said casing, whereby said spring contact member will be pressed into engagement with said contact post when pressure is brought to bear on said plunger. 90

JOHN E. W. FOGAL.
